EVERETT G. McDONOUGH, OF MOUNT VERNON, NEW YORK, ASSIGNOR TO ZOTOS CORPORATION, OF NEW YORK, N. Y., A CORPORATION OF NEW YORK

HAIR WAVING PAD

Application filed January 4, 1933. Serial No. 650,079.

This invention relates to certain improvements in hair waving pads for use where a pre-formed tress of hair is subjected to the action of an exothermic material contained within the pad, which exothermic material when moistened will, of itself, generate heat sufficient to impart a so-called permanent wave to the pre-formed tress.

My improved hair waving pad comprises 10 an outer wrapper, an envelope containing an exothermic material and having a perforated face, a removable sealing sheet adhered to the perforated face of the envelope for sealing its perforations, an absorbent sheet adapted to be placed upon the perforated face of the envelope after the sealing sheet has been stripped therefrom, and an inner flap adapted to be folded over onto the moistened sheet.

20 The object of my invention is to produce a hair waving pad of the above character in which the step of perforating the envelope containing the exothermic material immediately before the application of moisture thereto, is eliminated, thus permitting the pad to be shipped with the face of the envelope already perforated and temporarily sealed.

Practical embodiments of my invention 20 are represented in the accompanying drawing, in which:

Fig. 1 represents an inside plan view of one form of pad;

Fig. 2 represents a similar view of another form of pad;

Fig. 3 represents a similar view of a third form of pad; and

Fig. 4 represents a similar view of a fourth form of pad.

40 The outer wrapper 1 of the pad is shown as comprising a once folded sheet of impervious material, such for instance as parchment paper, foil, or the like.

The envelope 2 which contains the exothermic material 3, such for instance as calcium oxid in powdered form, has its face perforated as shown at 4. This envelope is also of impervious material, such for instance as foil.

50 A removable sheet 5 of impervious non-

soluble material, as foil, is placed upon and adhered to the perforated face of the envelope 2 for sealing the perforations 4. The sealing adhesive may be of some suitable material, such for instance as petroleum 55 jelly, which will not injuriously affect the pre-formed hair tress or the exothermic action of the material within the envelope, when the pad is in use.

A sheet 6 of absorbent material is shown 60 as a flap projecting from the pad in position to be moistened and then folded over onto the perforated face of the envelope 2 after the loose sealing sheet 5 has been stripped from the perforated face of the 65 envelope.

A sheet 7 of impervious material, such for instance as foil, is interposed between the envelope 2 and the outer wrapper 1, which sheet is shown as extended to produce 70 a foldably flap 8 adapted to be folded over onto the moistened absorbent flap 6 after the flap has been folded over onto the perforated face of the envelope.

In the forms shown in Figs. 1 and 3, the 75 flap 8 is perforated to permit a more direct action of the heat upon the pre-formed tress when the pad is applied thereto, the perforation in the said sheet being denoted by 9. In the forms shown in Figs. 2 and 4, 80 this flap 8 is unperforated to cause a less direct heat action upon the pre-formed tress.

In practice, the pre-formed tress of hair, not shown herein, may be moistened, either before or after it is wound, with a suitable 85 hair waving solution. The loose sealing sheet 5 is stripped from the perforated face of the envelope containing the exothermic material. The absorbent flap 6 is moistened and folded over onto the perforated face of the envelope. The inner flap 8 of the sheet 7 is then folded over onto the moistened flap 6. In some instances where a less direct heat action on the pre-formed tress is desired, the removable sealing sheet 5 may either be 90 placed on the moistened sheet 6 or wrapped around the pre-formed tress before the pad is applied. The pad is then wrapped around the pre-formed tress in the usual manner and the exothermic action starts at once. 100

Heat is thus set up within the pad sufficient to impart a so-called permanent wave to the pre-formed tress without requiring application of heat from an outside source.

- 5 It will be seen that in the forms shown in Figs. 1 and 2, the removable sealing sheet 5 projects beyond the end of the inner flap 8, thus permitting the sealing sheet when being stripped from the perforated face 10 of the envelope 2, to also unfold the inner flap 8. In the form shown in Figs. 3 and 4, the removable sealing sheet is shown as projecting beyond the side edge of the inner flap 8 of the sheet 7, thus requiring first that 15 the inner flap 8 be turned back before the said removable sheet is stripped from the perforated face of the envelope.

From the above description it will be seen that by sealing the perforated faces of the 20 envelopes containing the exothermic material, the pads may be shipped in quantities and the exothermic material protected from deterioration by exposure to varying atmospheric conditions until the time comes for 25 using the pads.

It is evident that various changes may be resorted to in the construction, form and arrangement of the several parts without departing from the spirit and scope of my 30 invention, and hence I do not wish to be limited to the particular embodiments herein shown and described, but what I claim is:

1. A hair waving pad comprising an outer wrapper, an exothermic material containing 35 envelope having its face perforated, a removable sealing sheet adhered to the perforated face of the envelope, an absorbent sheet adapted to be placed upon the perforated face of the envelope after the sealing sheet has been stripped therefrom, and an inner flap adapted to be folded over onto the moistened sheet.

2. A hair waving pad comprising an outer wrapper, an exothermic material containing 45 envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner flap adapted to be folded over onto the moistened sheet.

3. A hair waving pad comprising an outer wrapper, an exothermic material containing 55 envelope having its face perforated, a removable sealing sheet adhered to the perforated face of the envelope, an absorbent sheet adapted to be placed upon the perforated face of the envelope after the sealing sheet has been stripped therefrom, and an inner perforated flap adapted to be folded over onto the moistened sheet.

4. A hair waving pad comprising an outer 65 wrapper, an exothermic material contain-

ing envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner perforated flap adapted to be folded over onto the moistened sheet.

5. A hair waving pad comprising an outer wrapper, an exothermic material containing 70 envelope having its face perforated, a removable sealing sheet adhered to the perforated face of the envelope, an absorbent sheet adapted to be placed upon the perforated face of the envelope after the sealing sheet has been stripped therefrom, and an inner unperforated flap adapted to be folded over onto the moistened sheet.

6. A hair waving pad comprising an outer 75 wrapper, an exothermic material containing envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner unperforated flap adapted to be folded over 80 onto the moistened sheet.

6. A hair waving pad comprising an outer 85 wrapper, an exothermic material containing envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner unperforated flap adapted to be folded over 90 onto the moistened sheet.

7. A hair waving pad comprising an outer 95 wrapper, an exothermic material containing envelope having its face perforated, a removable sealing sheet adhered to the perforated face of the envelope, an absorbent flap adapted to be folded over onto the perforated face of the envelope after the sealing sheet has been stripped therefrom, and an inner flap adapted to be folded over 100 onto the moistened sheet.

7. A hair waving pad comprising an outer 105 wrapper, an exothermic material containing envelope having its face perforated, a removable sealing sheet adhered to the perforated face of the envelope, an absorbent flap adapted to be folded over onto the perforated face of the envelope after the sealing sheet has been stripped therefrom, and an inner flap adapted to be folded over onto the moistened sheet.

8. A hair waving pad comprising an outer 110 wrapper, an exothermic material containing envelope having its face perforated, a removable sealing sheet of impervious non-soluble material adhered to the perforated face of the envelope, an absorbent flap adapted to be folded over onto the perforated face of the envelope after the sealing sheet has been stripped therefrom, and an inner flap adapted to be folded over 115 onto the moistened sheet.

9. A hair waving pad comprising an outer 120 wrapper, an exothermic material containing envelope having its face perforated, a removable sealing sheet adhered to the perforated face of the envelope, an absorbent flap adapted to be folded over onto the perforated face of the envelope after the sealing sheet has been stripped therefrom, and an inner perforated flap adapted to be folded over 125 onto the moistened sheet.

10. A hair waving pad comprising an outer 130 wrapper, an exothermic material containing envelope having its face perforated, a removable sealing sheet of impervious

non-soluble material adhered to the perforated face of the envelope, an absorbent flap adapted to be folded over onto the perforated face of the envelope after the sealing sheet has been stripped therefrom, and an inner perforated flap adapted to be folded over onto the moistened sheet.

11. A hair waving pad comprising an outer wrapper, an exothermic material containing envelope having its face perforated, a removable sealing sheet adhered to the perforated face of the envelope, an absorbent flap adapted to be folded over onto the perforated face of the envelope after the sealing sheet has been stripped therefrom, and an inner unperforated flap adapted to be folded over onto the moistened sheet.

12. A hair waving pad comprising an outer wrapper, an exothermic material containing envelope having its face perforated, a removable sealing sheet of impervious non-soluble material adhered to the perforated face of the envelope, an absorbent flap adapted to be folded over onto the perforated face of the envelope after the sealing sheet has been stripped therefrom, and an inner unperforated flap adapted to be folded over onto the moistened sheet.

13. A hair waving pad comprising an outer wrapper, an exothermic material containing envelope having its face perforated, a removable sealing sheet adhered to the perforated face of the envelope, an absorbent sheet adapted to be placed upon the perforated face of the envelope after the sealing sheet has been stripped therefrom, and an inner flap adapted to be folded over onto the moistened sheet, the sealing sheet projecting beyond the end of the inner flap.

14. A hair waving pad comprising an outer wrapper, an exothermic material containing envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner flap adapted to be folded over onto the moistened sheet, the sealing sheet projecting beyond the end of the inner flap.

15. A hair waving pad comprising an outer wrapper, an exothermic material containing envelope having its face perforated, a removable sealing sheet adhered to the perforated face of the envelope, an absorbent sheet adapted to be placed upon the perforated face of the envelope after the sealing sheet has been stripped therefrom, and an inner perforated flap adapted to be folded over onto the moistened sheet, the sealing sheet projecting beyond the end of the inner flap.

16. A hair waving pad comprising an outer wrapper, an exothermic material con-

taining envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner perforated flap adapted to be folded over onto the moistened sheet, the sealing sheet projecting beyond the end of the inner flap.

17. A hair waving pad comprising an outer wrapper, an exothermic material containing envelope having its face perforated, a removable sealing sheet adhered to the perforated face of the envelope, an absorbent sheet adapted to be placed upon the perforated face of the envelope after the sealing sheet has been stripped therefrom, and an inner flap adapted to be folded over onto the moistened sheet, the sealing sheet projecting beyond the side edge of the inner flap.

18. A hair waving pad comprising an outer wrapper, an exothermic material containing envelope having its face perforated, a removable sealing sheet of impervious non-soluble material adhered to the perforated face of the envelope, an absorbent sheet adapted to be placed upon the perforated face of the envelope after the sealing sheet has been stripped therefrom, and an inner flap adapted to be folded over onto the moistened sheet, the sealing sheet projecting beyond the side edge of the inner flap.

19. A hair waving pad comprising an outer wrapper, an exothermic material containing envelope having its face perforated, a removable sealing sheet adhered to the perforated face of the envelope, an absorbent flap adapted to be folded over onto the perforated face of the envelope after the sealing sheet has been stripped therefrom, and an inner flap adapted to be folded over onto the moistened sheet, the sealing sheet projecting beyond the side edge of the inner flap.

20. A hair waving pad comprising an outer wrapper, an exothermic material containing envelope having its face perforated, a removable sealing sheet of impervious non-soluble material adhered to the perforated face of the envelope, an absorbent flap adapted to be folded over onto the perforated face of the envelope after the sealing sheet has been stripped therefrom, and an inner flap adapted to be folded over onto the moistened sheet, the sealing sheet projecting beyond the side edge of the inner flap.

In testimony, that I claim the foregoing as my invention, I have signed my name this 29th day of December, 1932.

EVERETT G. McDONOUGH.
